Primary Examiner — Susan Moon Lee(74) *Attorney, Agent, or Firm* — Young & Thompson(57) **CLAIM**

The ornamental design for an electronic camera, as shown and described.

DESCRIPTION

FIG. 1 is a front view of an electronic camera according to a first embodiment of the present design;

FIG. 2 is a rear view thereof;

FIG. 3 is a top view thereof;

FIG. 4 is a bottom view thereof;

FIG. 5 is a left side view thereof;

FIG. 6 is a right side view thereof.

FIG. 7 is a front view of the electronic camera according to a second embodiment of the present design;

FIG. 8 is a rear view thereof;

FIG. 9 is a top view thereof;

FIG. 10 is a bottom view thereof;

FIG. 11 is a left side view thereof; and,

FIG. 12 is a right side view thereof.

Broken lines and unshaded portions contained within broken lines are not claimed.

1 Claim, 6 Drawing Sheets## Related U.S. Application Data

of application No. 29/415,561, filed on Mar. 12, 2012, now Pat. No. Des. 681,652, which is a division of application No. 29/384,841, filed on Feb. 4, 2011, now Pat. No. Des. 659,152, which is a division of application No. 29/363,591, filed on Jun. 11, 2010, now Pat. No. Des. 633,509, which is a division of application No. 29/350,551, filed on Nov. 18, 2009, now Pat. No. Des. 622,729, which is a division of application No. 29/274,033, filed on Mar. 22, 2007, now Pat. No. Des. 609,714.
